UNITED STATES PATENT OFFICE.

WILLIAM HENRY NEAL, OF LONDON, ENGLAND.

PIPE FOR REGULATING THE SMOKING OF TOBACCO.

1,297,895.

Specification of Letters Patent. Patented Mar. 18, 1919.

Application filed July 11, 1914. Serial No. 850,438.

To all whom it may concern:

Be it known that I, WILLIAM HENRY NEAL, a subject of the King of Great Britain and Ireland, and residing at 12 Camomile street, London, E. C., England, have invented certain new and useful Improvements in or Relating to Pipes for Regulating the Smoking of Tobacco, of which the following is a specification.

10 This invention relates to covers for tobacco pipes and is applicable more particularly to the type of cover in which a hollow plug of metal, or other suitable material, is made to fit into the bowl of a pipe, being fixed therein by a screw thread and having a valve on the top of the plug to regulate the admission of air. One object of this present invention is to make an improved construction of plug or cover, where-
20 in springs and projections bearing against the interior of the bowl are employed. For this purpose the plug portion that fits into the bowl is made in the shape of a thin metal ring extending from the horizontal
25 flange which rests upon and covers the bowl. The ring is cut to form a plurality of spring strips or tongues the ends of which are shaped to form tapered studs extending outwardly. The turns may be cut diagonally
30 as desired. When the cover is pushed into the bowl of the pipe the taper studs on the ends of the tongues press against the inside of the bowl, thus holding the cover in position and enabling its being easily removed
35 for recharging the pipe and closing it again when lighted. By means of this arrangement one size of cover may be fitted and used with different sized bowls. The flange is provided with a central hole or aperture
40 having an upwardly extending wall into which a bowl-shaped valve member is inserted, being preferably held therein by friction. The valve member is provided with a lateral orifice through which air may pass,
45 being regulated according to the position of the valve member relatively to the surrounding wall.

In the accompanying sheet of drawings, illustrating the invention to a scale of about twice the correct size,

Figure 1 is an elevation of my improved cover,

Fig. 2 being a sectional elevation showing the operation of the valve member.

Fig. 3 is an elevation of a modified form. 55

In Figs. 1 and 2 *a* is the cover or flange for closing the bowl and *c* is the plug or ring extending from the same into the bowl. *e* are the taper plugs or studs fixed to or formed with the spring strips or tongues *f* 60 cut from the sides of the ring *c* in a diagonal direction. The plugs or studs *e* which are forced by the strips into frictional contact with the inside of the bowl by the strips *f* thus permit of the cover being 65 forced into its locked position on the bowl and also being withdrawn from the latter for charging it with tobacco. *g* is the bowl-shaped valve member located in the upwardly extending wall *h* which surrounds 70 the aperture *k* in the flange *a*. The valve member *g* is provided with a lateral air hole or orifice *o*, which is opened by raising the valve as shown in Fig. 2 and pushed down for closing the same as in Fig. 1. In Fig. 75 3 the plugs or studs *e* are carried by the spring strips *f* cut from the ring *c* in a vertical instead of a diagonal direction.

Having now described my invention what I claim as new and desire to secure by Letters Patent is:-

A cover for tobacco pipes consisting of two parts, one of which comprises a horizontal flange adapted to rest upon and close the bowl of the pipe and having an aperture 85 therein, an upwardly extending wall surrounding said aperture and a downwardly extending ring portion having strips cut therein, said strips being provided with outwardly projecting studs, the other part comprising a bowl-shaped valve member having a lateral orifice and being adapted to operate 90 in said walled aperture whereby the supply of air may be regulated as set forth.

In testimony whereof I have signed my 95 name to this specification in the presence of two subscribing witnesses.

WILLIAM HENRY NEAL.
